UNITED STATES PATENT OFFICE.

RUDOLF EISERMANN, OF BERLIN, GERMANY, ASSIGNOR TO INTERNATIONALE ROTATIONS-MASCHINEN GESELLSCHAFT M. B. H., OF BERLIN, GERMANY.

PISTON-DRUM FOR ROTARY ENGINES.

985,987.

Specification of Letters Patent.

Patented Mar. 7, 1911.

Application filed May 18, 1910. Serial No. 562,059.

To all whom it may concern:

Be it known that I, RUDOLF EISERMANN, engineer, a subject of the King of Prussia, residing at Berlin, Germany, have invented 5 certain new and useful Improvements in Piston-Drums for Rotary Engines; and I do hereby declare the following to be a full, clear, and exact description of the invention, such as will enable others skilled in the 10 art to which it appertains to make and use the same, reference being had to the accompanying drawings, and to letters or figures of reference marked thereon, which form a part of this specification.

15 My invention relates to the structure of the piston drums or rotors of rotary engines and similar machines, and has for its object to render such rotors stiffer than at present constructed to prevent the gripping 20 or binding of the blades or abutment slides mounted in the radial slots thereof.

25 Referring to the drawings, in which like parts are similarly designated—Figure 1 is a front elevation, partly in section, of a rotor embodying one form of my invention. Fig. 2 is a side elevation thereof. Fig. 3 is a view similar to Fig. 1, of a modification, and Fig. 4 is a side elevation of Fig. 3.

30 In those types of rotors for rotary engines and the like, in which the piston slides move either axially or radially in the rotor, the rotor is slotted radially from its periphery toward its center. The slides are mounted in and slidable in those slots which 35 sub-divide the core or rotor into segments connected together at or near the center of the rotor, whereby there is only a very small thickness of metal at the bases of the slots to hold the sectors together, as, for example, the small thickness of metal marked 40 α in Fig. 2. Though fractures at these endangered points are not to be feared, as the pressure on one slide will, at the least deformation of the drum sector receiving such 45 pressure, be transferred to the other sectors by the intermediary of the other slides, such transference of pressure produces considerable gripping between the slides and their ways, so that correspondingly great losses 50 by friction are caused, and the slides may stick and be damaged in consequence thereof.

According to the present invention I provide distance pieces at suitable points, for the purpose of preventing the spring of the

sectors and the consequent gripping or sticking of the slides. In such instances where the slots do not afford sufficient space for the arrangement of such distance pieces, the drum may be enlarged at a suitable point, and the distance pieces may then be arranged in those parts of the slots which are situated within such enlargement.

Figs. 1 and 2 of the accompanying drawing exemplify a form for carrying out the present invention in a piston drum or rotor 65 a , which is provided as in U. S. Patent No. 894,391, with concentric working grooves b turned in the end surface of the rotor, and radial longitudinal grooves c for receiving the radially moving piston slides g , which have 70 notches h corresponding to the grooves b . The slots c subdivide the rotor into the sectors h between them and extend almost to the central shaft, leaving but a small body of metal between the grooves at the inner 75 ends of the slots, so that these sectors will bend at these points when sufficient pressure is placed on the slides in the slots. To obviate this, I fit in each groove or slot c in the center of the outer longitudinal edge 80 thereof a piece d , so that each two adjoining sectors of the piston drum cannot alter their distance from each other, and the slides can therefore not be gripped by the spring of the sectors.

85 The abutment slides or piston slides g must be provided with notches i , Fig. 1, considerably deeper, or having a radial length considerably longer than the depth or radial length of the pieces d that are fitted into 90 the outer portions of the slots c to prevent the sector-shaped portions of the rotor between the slots c from springing or yielding when pressure is applied to the slides by reason of the fluid used in the machine. 95 Such notches i permit the slides g to be properly moved in their slots without being hindered by the pieces d inserted in the outer ends of the slots. The constructional form shown in Figs. 1 and 2, is therefore, 100 generally, only applicable when the bottoms of the oppositely situated concentric grooves b in the opposite ends of the rotor are comparatively wide apart, as shown in Fig. 1. If the bottoms of the grooves b on the opposite sides of the rotor are close together, so as to leave but a thin web of metal between them, as in Fig. 3, then I provide the rotor 105

or drum with a collar-shaped enlargement *e* at its middle, as shown in Figs. 3 and 4. This collar-shaped enlargement is narrower than the length of the rotor and is provided with slots that register with and form extensions of the slots *c* in the rotor. The pieces *d* are then placed in these extensions of the slots *c* in the part *e*. A ring *f* is then placed around the collar-shaped enlargement to which the pieces *d* are secured if necessary. Thus it will be seen that the rotor of any rotary fluid machine that has abutment slide slots of the character described will be materially improved by the application of my invention, the slots will be effectually prevented from contracting by the pieces *d*, due to the spring of the sector-shaped portions of the rotor springing when the piston slides or abutment slides are under load, thereby preventing said slides from becoming clamped or sticking in their slots.

I claim—

1. The combination with a piston drum or rotor for rotary engines having radial slots for slide pistons; of distance pieces arranged in said slots to prevent the slots from altering in width.
2. The combination with a piston drum or rotor for rotary engines having radial slots for slide pistons; of distance pieces arranged in said slots near their outer edges.
3. The combination with a piston drum or rotor for rotary engines having radial slots for slide pistons; of a ring laid around

said drum and distance pieces arranged in said slots and attached to said ring.

4. The combination with a piston drum or rotor for rotary engines having radial slots for slide pistons; of a collar-shaped enlargement on the drum having slots registering with those in the drum and distance pieces in the slots of said enlargement.

5. The combination with a piston drum or rotor for rotary engines having radial slots for slide pistons; of a collar-shaped enlargement on the drum having slots registering with those in the drum, a ring laid around said enlargement, and distance pieces arranged in the slots of said enlargement.

6. The combination with a piston drum or rotor for rotary engines having radial slots for slide pistons; of a collar-shaped enlargement on the drum having slots registering with those in the drum, a ring laid around said enlargement and distance pieces arranged in the slots of said enlargement and secured to said ring.

7. The combination with a piston drum or rotor for rotary engines having radial slots for slide pistons; of a ring laid around said drum and distance pieces arranged in said slots.

In testimony that I claim the foregoing as my invention, I have signed my name in presence of two subscribing witnesses.

RUDOLF EISERMANN.
